(57) **CLAIM**

The ornamental design for a multifunctional orthodontic tool, as shown and described.

DESCRIPTION

FIG. 1 is a perspective view of a multifunctional orthodontic tool;

FIG. 2 is a top plan view of the multifunctional orthodontic tool shown in FIG. 1;

FIG. 3 is a bottom plan view of the multifunctional orthodontic tool shown in FIG. 1;

FIG. 4 is a left side view of the multifunctional orthodontic tool shown in FIG. 1;

FIG. 5 is a right side view of the multifunctional orthodontic tool shown in FIG. 1;

FIG. 6 is a front view of the multifunctional orthodontic tool shown in FIG. 1;

FIG. 7 is a rear view of the multifunctional orthodontic tool shown in FIG. 1; and,

FIG. 8 is another perspective view of the multifunctional orthodontic tool shown in FIG. 1 with several orthodontic tools exposed.

The elements shown in broken lines are to show environment and form no part of the claimed design.
